(57) **CLAIM**

The ornamental design for a skin cover set for a gaming console, as shown and described.

DESCRIPTION

FIG. 1 is an elevation view of a skin cover set for a gaming console showing my new design;

FIG. 2 is a side elevation view thereof; and,

FIG. 3 is an elevation view showing the skin cover set for a gaming console in condition of use of FIG. 1.

The broken lines in the drawings depict environmental structure of a gaming console and form no part of the claimed design.

1 Claim, 3 Drawing Sheets
